Primary Examiner — Austin Murphy(74) *Attorney, Agent, or Firm* — Lora J. Graentzdoerffer; Nirav D. Parikh; Edgar A. Zarins(57) **CLAIM**

The ornamental design for a fastening tool, as shown and described.

DESCRIPTION

FIG. 1 is a perspective view thereof;
 FIG. 2 is an alternative perspective view thereof;
 FIG. 3 is a right side elevational view thereof; the left side elevational view being a mirror image thereof;
 FIG. 4 is a front elevational view thereof;
 FIG. 5 is a rear elevational view thereof;
 FIG. 6 is a top plan view thereof; and,
 FIG. 7 is an enlarged perspective view of a portion of FIG. 1. The broken-line disclosure in the views represents portions of the article in which the claimed design is embodied, but which form no part of the claimed design.
